UNITED STATES PATENT OFFICE.

OSCAR HENDLER, OF VIENNA, AUSTRIA.

HOLDER FOR CIGARETTES AND CIGARS.

Application filed December 4, 1923. Serial No. 678,506.

To all whom it may concern:

Be it known that I, OSCAR HENDLER, a citizen of the Austrian Republic, and residing at 44 Hameaustrasse, Sallmannsdorf, Vienna, XVIII, Austria, have invented certain new and useful Improvements in and Relating to Holders for Cigarettes and Cigars, of which the following is a specification.

10 It has already been proposed to make cigar holders, in which the sucking in of air between the cigar and the holder is prevented by the cigar being inserted into a central opening in an elastic annular disc, the rim 15 of the opening being thereby expanded and thus caused to hold the cigar firmly. Such holders have the disadvantage that they are almost useless for cigarettes, owing to the fact that, through the forcible expansion of 20 the edge of the opening in the elastic disc by the cigarette to be inserted, the latter is bound to be damaged, while it is very difficult to remove the cigarette or cigar end from the holder, as it can only be released 25 from the member holding it by a vigorous pull.

The disadvantages are avoided in the cigarette or cigar holder according to the present invention, by the elastic packing insertion having the form of a sleeve, ring of approximately circular cross-section or the like and being adapted to be pressed by means of a screw cap or a slip-on cap against an abutment provided at the front of the 30 opening in the holder, whereby the internal diameter of the elastic packing piece is reduced and the inner edge of the same is caused to press firmly against the cigarette or the like, while, on the cap being released, the internal diameter of the packing insertion becomes greater again, so that the cigarette or cigar end can be removed from the holder without effort.

In the accompanying drawing the invention is illustrated by several constructional examples in longitudinal section.

Figure 1 is a part sectional elevation of a cigarette holder provided with a packing in the form of a sleeve and with a screw cap.

50 Figure 2 illustrates the front end of a modification of the cigarette holder in sectional elevation with a screw-cap and a packing in the form of a ring of approximately circular cross section.

55 Figure 3 illustrates in sectional elevation a modification of the front part of the cigarette holder showing a slip-on cap and a packing in the form of a sleeve, and

Figure 4 is a longitudinal section of the slip-on cap carrying the packing sleeve illustrated in Figure 3.

In the constructional form shown in Fig. 1 in the bore *a* of the holder *b* a part *c* is inserted, which part has a central hole and is provided with an external thread, on which the internally threaded part of a cap *d* is screwed. The cap *d* is provided with an internal sleeve *e* of rubber or other elastic material, which is slightly thinned down at the inner end and into which the cigarette or cigar is loosely inserted. The insertion piece *c* has an internal conical surface *f*, on which the thinned-down edge of the elastic sleeve *e* bears, on the sleeve *d* being screwed in, i. e. being displaced towards the mouth-piece of the holder, thus causing the sleeve to be forced inwards and its internal diameter to be reduced. The consequence of this is, that the sleeve *e* is caused to fit tightly around the cigarette or cigar and holds the same firmly. When the cigarette has been smoked, the cap *d* is raised by being turned and the sleeve *e* returns to its normal position, its internal diameter becoming greater, so that the cigarette end can be removed 85 from the holder without trouble by blowing or by simply knocking.

In the constructional form shown in Fig. 2 the cap *d*, which is screwed on to a threaded ring *g*, contains an elastic non-flat ring *e¹*, which, on the sleeve *d* being screwed in, comes against the end surface *f¹* of the holder *b*, is thereby compressed and reduced in its internal diameter, by which means the cigarette *h* is held firmly and in an air-tight manner against the holder *b* by the ring *e¹*.

According to Fig. 3 the conical abutment surface *f²* is not formed on a separate member as in Figure 1, but directly on the internal wall of the holder. In this case the cap *d* is not displaced by being screwed, but by being displaced axially, the part of the cap surrounding the holder *b* being slotted and therefore somewhat resilient, so that it can be clamped on the holder *b* to a greater or less depth, whereby the internal diameter of the packing sleeve may be varied.

In Fig. 4 another form of the cap *d* is shown. This form is provided, similarly to the cap shown in Fig. 3, with a resilient 110 rim and the packing sleeve *e* is held in the cap by the wall of the cap being beaded over

inwardly, which at the same time protects the sleeve from being affected by the burning cigarette or cigar.

As the provision of the displaceable cap increases the length of the hollow space *a* in the holder, a pad of wadding can easily be inserted in these holders, without interfering with the firm grip exerted by the holder on the cigarette.

10 Other modifications of the cigarette or cigar holder according to the invention are possible, without departing from the spirit of the invention.

What I claim is:—

15 1. A holder for cigarettes and cigars, comprising in combination a hollow stem, an abutment surface at one end of the said stem, a cap having a central bore and capable of being placed on the said end of the stem and moved axially with respect to the latter and an elastic annular packing member in the said cap capable of being pressed against the said abutment surface whereby

the inner diameter of the annular packing ring is reduced and its inner surface is 25 pressed firmly against the cigarette or cigar, whilst when the cap is removed the said inner diameter is again increased owing to the elastic properties of the ring so that the end 30 of the cigarette or cigar can be easily removed, as and for the purpose set forth.

2. A holder for cigarettes and cigars, comprising in combination a hollow stem, a conical abutment surface at one end of the said stem, a cap having a central bore and 35 capable of being placed on the said end of the stem and moved axially with respect to the latter and an elastic sleeve in the said cap having its end facing the conical abutment surface thinner than the rest of the 40 sleeve and capable of being pressed against the said abutment surface, as and for the purpose set forth.

In testimony whereof I have signed my name to this specification.

OSCAR HENDLER.
